Lurelle Guild, Darien, Conn., assignor to Aluminum Company of America, Pittsburgh, Pa., a corporation of Pennsylvania

Application September 9, 1953, Serial No. 26,753

Term of patent 14 years

(Cl. D44—1)

To all whom it may concern:

Be it known that I, Lurelle Guild, a citizen of the United States, residing at Darien, in the county of Fairfield and State of Connecticut, have invented a new, original, and ornamental Design for a Cooking Pan, of which the following is a specification, reference being had to the accompanying drawing, forming a part thereof, in which:

Fig. 1 is a side elevational view of a cooking pan embodying my new design,

Fig. 2 is a top plan view thereof,

Fig. 3 is a cross sectional view of the handle taken on the line III—III of Fig. 1; and

Fig. 4 is a cross sectional view of the handle attaching member taken on the line IV—IV of Fig. 1.

I claim:

The ornamental design for a cooking pan, substantially as shown.
